UNITED STATES PATENT OFFICE

2,553,807

BED SLAT HANGER

William G. Brands, Glendale, Calif.

Application April 14, 1947, Serial No. 741,229

4 Claims. (Cl. 5—238)

1

This invention relates to an attachment for furniture, and particularly pertains to a bed slat hanger.

In furniture manufacture the ordinary bed is provided with a ledge along the inside of the bed rail for receiving transversely disposed slats. These slats of course are provided to support the springs and mattress. It often occurs that the slats do not remain in positions parallel to each other and the head and foot-board of the bed and assume angular positions which allow one or the other end of the slat to slip off of the supporting edge, and thus deprive the springs of support. In some instances it is desirable to support the springs and mattress at different heights from the floor and with relation to the upper edges of the bed rails. For example, with sick or elderly persons, it may be desirable to place the slats in an extremely low supporting position so that a person may get in or out of the bed easily. In some cases it may be desirable to support the slats in an extremely high position so that it would be easier to take care of a bedfast patient. It is desirable, therefore, to provide a means of supporting bed slats which will prevent them from becoming dislodged when in their supporting positions, and which supporting structure will make it possible to provide a hanger designed to support a bed slat in a desired horizontal plane. It is the principal object of the present invention, therefore, to provide a bed slat hanger which may be very cheaply manufactured and which may be instantly mounted upon the side rails of a bed to receive the end of a bed slat and to hold the end of the bed slat against dislodgment, the structure being light in weight and of a design which makes it possible for the hanger to be applied to a bed rail without the use of any screws or other like fastening means.

The present invention contemplates the provision of a bed slat hanger which is preferably formed from a piece of sheet metal of a configuration to permit it to be easily folded to form a hanger member and a slat receiving pocket, the structure having means engaging the edge of a bed rail to dispose the pocket at a point between the bed rails and into the ends of which pockets a slat may be seated.

The invention is illustrated by way of example in the accompanying drawings in which:

Figure 1 is a view in perspective showing a fragmentary portion of a bed rail, the slat hanger with which the present invention is concerned, and a fragmentary portion of a bed slat positioned within the pocket of the hanger.

2

Fig. 2 is a view in plan showing the sheet metal blank from which the hanger is formed.

Referring more particularly to the drawings, 10 indicates the rail of a bedstead. The rail is 5 here shown as being made of wood although it will be understood that the device embodying the present invention could be designed for use with metal rails. The upper edge of the rail 10 is here shown as being slightly rounded. This 10 is merely an example of the bed rail construction and it is obvious that other configurations could be given to the edge of the rail. The device with which the present invention is concerned is the hanger 11 to receive a bed slat 12. 15 The hanger is made from a flat sheet of metal shown in Fig. 2 of the drawing. The metal is cut to form a T-shaped blank 13 having a center portion 14 and opposite lateral portions 15 and 16 at one end thereof. The center portion 14 is curved or hooked to form a rail engaging end 17. At the opposite end of the center portion 14 from the rail engaging end 17 the portion 14 is bent along a transverse line indicated by the dotted line 18 in Fig. 2. This line occurs between 20 and in alignment with edges of the lateral portions 15 and 16. The lateral portions 15 and 16 are bent along the fold lines indicated by dotted lines 19 and 20 which are in alignment with the opposite longitudinal edges of the center portion 14. As shown in Fig. 1, the lateral portions are bent upwardly and parallel to each other to form wall sections 21, after which the free ends of the lateral portions 15 and 16 are bent over to positions parallel to each other and 25 to provide top flanges 22. These portions are bent over on fold lines 23, as indicated in Fig. 2. It will thus be seen that when the lateral portions are bent, as shown in Fig. 1, a pocket 24 will be provided, the cross-sectional dimensions of which are such as to accommodate the slats 12. It will also be seen that the intermediate section of the center portion 14, as indicated at 14', will be bent along the line 18 to assume a position at right angles to the portion 14. This will cause the edges of the lateral portions 15, which edges are in the same plane as the fold line 18, to lie flush against the vertical center portion 14 of the hanger. In order to give strength to the structure these 30 edges may be welded to the face of the center portion 14, as indicated at 25, and the abutting free edges of the lateral portions 14 and 15 may be welded together along the line 26.

It is to be understood that the vertical length 35 of the portion 14 may be as desired, and that the rail engaging portion 17 may be bent in any

suitable manner to conform to the contour of the upper edge of the rail. It is also to be pointed out that the depth of the pocket 24 which is represented by the width of the lateral portions 15 and 16 shall be sufficient to receive the end of a slat 12 and to prevent it from being dislodged therefrom after the slat hangers 11 have been placed in position along the rail. By this arrangement when slat hangers 11 have been placed upon opposite ends of a slat 12 and the assembled structure is disposed between the side rails 10 of a bedstead there will be no possibility for the hangers 11 to become disengaged from the rails of the bedstead and there will not be any possibility for the slats to become dislodged from the pockets 24 of the hangers. The construction of the hangers is such as to make it possible to easily manufacture the hanger with relatively long vertical center sections 14 or short vertical center sections 14. This will give selection in providing hangers for supporting a mattress high above the rails 10 or in a relatively low position down between the rails, as might be required under different circumstances.

In operation of the invention the hangers are made by first forming the T-shaped blank 13 and thereafter folding the blank along the fold lines 18, 19 and 20, and 23. This will form the pocket 24 and will dispose it at right angles to the vertical plane of portion 14. The hooked end 17 is formed as required. The edges 25 and 26 may be welded and the hanger will be ready for use. This is accomplished by placing complementary hangers upon opposite ends of a bed slat 12 and then disposing the slat with the hangers down between the rails 10, with the rail engaging portion 17 overhanging the upper edges of the rails. Springs and a mattress may then be placed upon the slats and will tend to hold the hangers 11 in their seated positions upon the rails 10. At the same time the depth of the pockets 24 will prevent the ends of the slats from being dislodged from the pockets.

It will thus be seen that the structure here disclosed may be made from a one-piece sheet metal blank which can be folded easily to form a hanger and a pocket, and which will receive and support a slat at a desired vertical position and without possibility that it will be dislodged from the pockets of the hangers.

While I have shown the preferred form of my invention as now known to me, it will be understood that various changes may be made in combination, construction and arrangement of parts by those skilled in the art, without departing from the spirit of the invention as claimed.

Having thus described my invention, what I claim and desire to secure by Letters Patent is:

1. A slat hanger for bedsteads, comprising a substantially flat portion designed to extend vertically along the inner side of a bed rail, a continuation thereof at the upper end of said portion bent to form a rail engaging section; a continuation of said flat portion at the lower edge thereof bent in the opposite direction of the upper section and forming a ledge upon which a slat may rest, the opposite edges of said lower bent

portion which forms said ledge being folded upwardly parallel to each other and then folded toward each other to lie in a horizontal plane whereby a slat receiving pocket will be formed.

2. An individual slat hanger for bedsteads having a pair of longitudinal side rails, said hanger comprising a vertical sheet-metal portion adapted to conform to the inner wall of one of said side rails and having an outwardly and downwardly bent hook portion at the upper end thereof adapted to receive and conform to the upper marginal portion of said side rail, a slat pocket bottom wall portion formed integrally with and disposed at right angles to the vertical portion, a pair of vertical pocket side wall portions formed integrally with the pocket bottom and bent upwardly at right angles from said pocket bottom wall portion, the outer edges of said pocket side wall portions being disposed contiguous to the vertical portion, and a pair of pocket top tabs, one of which is formed integrally with each pocket side wall portion, said top tabs being bent inwardly toward each other to define with the pocket side and bottom walls a rectangular pocket adapted to receive the end of a bed slat therein, the outer end of the pocket being closed by the vertical portion to protect the bed side rail from contact by the end of the bed slat in said pocket.

3. The hanger defined in claim 2 wherein the top tabs are in endwise contiguous relation to each other, and in edgewise contiguous relation to the vertical portion.

4. The method of forming a T-shaped piece of sheet-metal into a hanger for a bed slat of predetermined thickness which comprises inverting the T-shaped piece of sheet-metal, bending the stem of the T at right angles to the head thereof on the line of juncture of the stem with the head, bending the two laterally extending end portions of the head upwardly alongside the sides of the stem portion of the T, bending the upper ends of the thus upbent side portions of the head inwardly toward each other at a height equal to the predetermined thickness of a bed slat, the inwardly bent portions being of a length less than the width of the stem of the T, and bending the upper end of the stem portion outwardly and downwardly to form a hook adapted to have close supporting engagement with the upper marginal portion of a bed rail.
